(57) **CLAIM**

The ornamental design for a lattice, as shown and described.

DESCRIPTION

FIG. 1 is an isometric view of a lattice of a novel design.

FIG. 2 is a front view of a lattice.

FIG. 3 is a top view of a lattice, the bottom view being identical thereto.

FIG. 4 is a right side view of the lattice, the left side view being identical thereto; and,

FIG. 5 is a rear view of a lattice.

The article in which the design is embodied is intended for use as a lattice.
